S. Polakoff
ATTORNEY

UNITED STATES PATENT OFFICE.

AUGUSTIN THIBERT, OF JOGUES, ONTARIO, CANADA.

CATTLE GUARD FOR RAILROADS.

Application filed March 26, 1928. Serial No. 264,809.

This invention relates to improvements in animal guards and particularly to those used to prevent cattle, or similar creatures from straying into areas which are not adaptable for fencing, as railroad and highway crossings, or passageways between adjacent pastures and the like.

Its object is to provide an improved means for accomplishing the above described purposes which shall be more effectual than the devices now in common use, and shall, not only hamper the animals attempting to pass over the device, but also alarm them by inflicting slightly painful contacts with the feet and the legs of the said animals.

The manner which the above objects are attained and the mechanical characteristics of the invention will be fully described in the following specification and illustrated in the accompanying drawings, in which:

Fig. 1 shows a front elevation of the elements of the device as applied in conjunction with a railroad track, the view being taken on the line 1—1 of Figure 2.

Fig. 2 shows a plan view of the elements illustrated in Figure 1.

Fig. 3 shows a form of the invention somewhat enlarged, in which certain parts are slidably mounted, the view being taken on the line 3—3 of Figure 4.

Fig. 4 shows a plan view of the mechanism illustrated in Figure 3 of the drawings.

Referring first to Figures 1 and 2, the device comprises a series of spur wheels as shown at 10, 11, 12, 13 etc., which are rotatably mounted on rods as shown at 14 and 15. Collars as seen at 16, 17 etc. are provided to maintain the said spur wheels in position. The supporting rods are mounted in vertical bearing brackets as shown at 19, 20 etc., which are secured to base strips as seen at 24 and 25. These strips are secured to the railroad ties as seen at 26 and 27, or to any suitable supporting medium. Railroad tracks 28 and 29 are shown together with the ties 26 and 27 to illustrate this form of installation, they are not elements of the invention, which may have other applications than that shown in connection with a railroad. The device may for instance, be built on a smaller

scale and used to protect certain spaces from the intrusion of dogs and other small animals.

The mechanism above described may be constructed of iron, or of any suitable materials, provision being preferably made to prevent rust, or corrosion from interfering with the working parts thereof.

The form illustrated in Figures 3 and 4 is constructed with the rods as 14, 15 etc., mounted in slots as seen at 31 and 32 in the vertical supports 33 and 34, which supports are the equivalent of the brackets shown in the preceding figures at 19 and 20. On the rods so mounted are links as seen at 35 and 36 which support the foot plates as seen at 37 and 38, these links being placed at intervals along the said plates as required.

It will be seen that should an animal try to pass over the guard as shown, the contact of its feet, or hoofs with the spur wheels would give such discomfort as to cause it to withdraw and abandon the attempt. The discomfort and retarding effect of the device as shown in Figures 1 and 2 would be greatly augmented by the arrangement shown in Figures 3 and 4 in which case a hoof placed on the foot plate would immediately draw the adjacent spur wheels against the sides of the animal's leg thereby applying the same startling treatment as is given by an equestrian wearing the conventional form of spurs.

The spur wheels may, if desired, be firmly secured to the rods, which would then rotate in the bearing brackets. This modification and similar minor departures in form, or construction may be made within the spirit and scope of the appended claims.

Having thus described my invention, what I claim as new and desire to secure by Letters Patent, is as follows:

1. In an animal guard, a series of rods placed parallel to each other and slidably mounted in vertical supporting members which are secured to a suitable base structure, rotatable members having spur points projecting radially therefrom and the said rotatable members mounted at intervals on the aforesaid rods, and foot plates positioned in the spaces intervening between the said rods.

and supported by links which connect them to adjacent portions of the said rods.

2. In an animal guard, parallel series of spur wheels rotatably mounted at intervals on rod members which are slidably supported in vertical bearing brackets, which brackets are secured to suitable base elements, and

foot plates in positions parallel to the said rods and supported therefrom by link members which are placed at intervals thereon. ¹⁰

In testimony whereof I have affixed my signature.

AUGUSTIN THIBERT.
